(57) **CLAIM**

The ornamental design for an electric hanging clothes dryer and cover, as shown and described.

DESCRIPTION

FIG. 1 is a perspective view of a combined electric hanging clothes dryer and cover showing my new design, the clothes cover being in a partially open position, the clothing shown in broken lines is for illustrative purposes only and form no part of the claimed design;

FIG. 2 is a side perspective view thereof, the clothes cover being removed;

FIG. 3 is an enlarged front view of the dryer portion of the design thereof, the support pole, extensions, and clothes cover being removed;

FIG. 4 is an enlarged top plan view of the dryer portion of the design thereof; and,

FIG. 5 is an enlarged perspective view of the dryer portion of the design thereof, the support pole, extensions, and clothes cover being removed.
